UNITED STATES PATENT OFFICE.

HARRY A. ATWOOD, OF SHEBOYGAN, WISCONSIN, ASSIGNOR TO THE CROCKER CHAIR COMPANY, OF SAME PLACE.

DESIGN FOR A CHAIR-TOP.

SPECIFICATION forming part of Design No. 33,664, dated December 4, 1900.

Application filed July 27, 1900. Serial No. 25,054. Term of patent 7 years.

To all whom it may concern:

Be it known that I, HARRY A. ATWOOD, a citizen of the United States, residing at Sheboygan, in the county of Sheboygan and State 5 of Wisconsin, have invented and produced a new and original Design for a Chair-Top; and I do hereby declare the following to be a full, clear, and exact description of the same, reference being had to the accompanying 10 drawings, forming a part thereof.

In the said drawings, Figure 1 is a plan view. Fig. 2 is a front elevation, and Fig. 3 is a vertical transverse sectional view taken on the line 3 3 of Fig. 1 of a chair-top embodying my new design.

My design relates to the new and original shape or configuration of the article.

As shown in the drawings, the leading or material feature of my design for a chair-top 20 consists of the elongated body A, cylindrical in cross-section and of equal diameter throughout and curved on the arc of a circle, but horizontally disposed from end to end

and provided with the rounded balls or knobs B B at the ends.

Minor features of my said design comprise the shape of the portions intermediate between the ends of the curved elongated body A and the balls or knobs B B—namely, the cylindrical portions b b next to the said ends 25 of and of less diameter than the body A, the annular portions c c next the balls or knobs B B, and intermediate concavely-grooved annular portions d d.

Having thus described my invention, what 30 I claim as new, and desire to secure by Letters Patent, is—

The design for a chair-top, substantially as herein shown and described.

In testimony whereof I affix my signature 35 in presence of two witnesses.

HARRY A. ATWOOD.
